The ornamental design for a container with cap, as shown and described.

DESCRIPTION

FIG. 1 is a perspective view of a container with cap showing our new design;

FIG. 2 is a first side elevation view thereof;

FIG. 3 is a second side elevation view thereof;

FIG. 4 is a top plan view thereof;

FIG. 5 is a bottom plan view thereof;

FIG. 6 is an exploded perspective view of the container with cap of FIG. 1 showing the container with cap separated and bound by a bracket;

FIG. 7 is a first side elevation view of the container portion shown in FIG. 6; and,

FIG. 8 is a second side elevation view thereof.

The broken lines in the drawings showing the container with cap illustrate portions of the container with cap that form no part of the claimed design.
